WHEEL WASHING APPARATUS

Henry A. Crivelli, Belmont, Mass.

Application February 16, 1956, Serial No. 565,805

13 Claims. (Cl. 15—302)

The present invention relates to washing apparatus and, more particularly, to automatic apparatus for effectively washing the wheels of an advancing column of automobiles or other motor vehicles that are being subjected to a sequence of washing operations in assembly-line fashion.

The object of the present invention is to provide automatic wheel-washing apparatus which effectively cleans the tires, hubs, etc. of wheels that, in the past, would have been too scuffed and soiled to be cleaned otherwise than under direct manual control. The automatic wheel-washing apparatus of the present invention comprises a bank of advantageously arranged and actuated rotatable brushes and cleaning-fluid ejection nozzles interspersed on an elongated base that is resiliently biased in parallelism toward the side of an advancing vehicle in order to clean successive adjacent regions of a given wheel rotating normally as the vehicle advances.

Other objects of the present invention will in part be obvious and will in part appear hereinafter.

The invention accordingly comprises the apparatus possessing the construction, combination of elements and arrangement of parts which are exemplified in the following detailed disclosure, and the scope of which will be indicated in the appended claims.

For a fuller understanding of the nature and objects of the present invention, reference should be had to the following detailed description taken in connection with the accompanying drawing wherein:

Figure 1 is a top plan view of a preferred embodiment of the present invention, showing the organization of the interspersed brushes and nozzles;

Fig. 2 is a front elevation of the embodiment of Fig. 1;

Fig. 3 is an enlarged top plan view of the embodiment of Fig. 1, with parts broken away and omitted;

Fig. 4 is a cross-section, taken substantially along the line 4—4 of Fig. 1;

Fig. 5 is a broken away detail view of the steam release mechanism associated with one of the nozzles; and

Fig. 6 is a detail side view of the steam release mechanism of Fig. 5.

The apparatus shown in the accompanying drawings as illustrative of the present invention generally comprises a plurality of rotatable brushes 20 and steam nozzles 22 interspersed in a row along a frame 24 which is cantilevered on a pair of parallel swivel arms 26 and which is biased for perpendicular movement with respect to its direction of elongation toward one side of a vehicle advancing from right to left as viewed in Fig. 1. This apparatus ordinarily is employed in association with its mirror replica which is biased toward the opposite side of the vehicle. 65

2

Frame 24 is constructed from sections of right angle stock which are mitered at their ends and welded together to form a parallelepiped having four long side lengths 28, four short end lengths 30 and four short end lengths 32. 5 Oppositely directed from upper and lower horizontal end lengths 30 and 32 are pairs of upper and lower extensions 34 and 36, respectively, which journal the forward ends of swivel arms 26. The rearward end of each arm 26 is journaled between a pair of blocks 38 secured to a stationary post 40. The foot of post 40 is affixed to a plate 42 which extends forwardly a considerable distance to prevent the weight of the frame from tilting the entire apparatus.

Brushes 20, which are sufficient in number and diameter to scrub the successive sectors of any standard automobile wheel completing one revolution, are keyed to shafts 44, which are journaled at the forward side lengths 28 by straps 46. At the upper ends of shafts 44 are drive sprockets 48 which mesh with a chain 50 internally of its loop. Chain 50 is driven by a motor 52 through an elbow transmission 54 and a drive sprocket 56 which meshes with the chain internally of its loop. The chain is maintained in taut condition by sprockets 58 which mesh with it externally of its loop. Motor 52 and transmission 54 are carried on a platform 60 secured to and movable with frame 24.

Nozzles 22, which have vertical discharge slits 62, are supplied with a detergent-and-steam mixture through a main line 64 which is fed, as seen in Fig. 1, at its left end, 30 that is, at its end that is farthest from the end of frame 24 that first contacts the wheel to be washed. Main line 64 feeds into successive pairs of nozzles through successive valves 66. As shown in Figs. 3 and 6, each valve is opened when a plunger 68 is urged against spring bias into the valve housing by a pivoted lever 70 having at its free end a roller 72. Valve 66 is gradually opened when actuated by a reciprocable rod 74 acting on roller 72 through a cam 76. Valve 66 is deactivated when roller 72 is released by cam 76.

40 A plurality of arms 78, one of which is shown in Fig. 5, serve (1) to limit forward movement of frame 24 toward a wheel being cleaned in order that scrubbing be effected only by the outer portions of brushes 20, and (2) to actuate the particular valves which control the discharge from 45 the pairs of nozzles 22 closest to this wheel in order to minimize the necessary pressure in main line 64. Arm 78 is pivoted at one end by means of a link 80 to the upper forward side length 28 of frame 24 in order to lie along the floor in position to contact the tire of the wheel. Arm 50 78 is medially pivoted to the forward end of rod 74. Arm 78 is biased forwardly by a spring 82 coiled about rod 74 in compression between upper rearward side length 28 and a collar 84. The forward end of rod 74, which is 55 threaded at 86, meshes with an adjusting nut 88 that limits the rearward movement of arm 78.

An oblique arm 90 is affixed to upper extension 36 to move frame 24 rearwardly an appropriate distance when initially contacted by the wheel of an advancing vehicle. 60 Arm 90 and, also, arms 78 are provided at their forward edges with elongated rollers 92 which adapt them to smoothly engage and disengage rotating portions of the wheel. A coil spring 93 connected between the center of frame 24 and one of posts 40 bias the frame outwardly.

A pair of nozzles 94 and 96 which have horizontal

discharge slits 98 are disposed at the center and at the wheel-disengaging end of the frame in order to clean the hub of the wheel which ordinarily requires no scrubbing. A nozzle 100 at the wheel disengaging end of frame 24 provides a flow of hot water for rinsing the entire wheel at the end of the cleaning operation.

In operation, an automobile, for example, advances from right to left, as viewed in Fig. 1, along the floor upon which plate 42 rests so that one of its right wheels engages roller 92 of arm 90. As a result, frame 24 is urged rearwardly, against the bias of spring 93, until the wheel contacts the first of levers 78. Gradually, this lever is pivoted rearwardly and steam is ejected from the first pair of nozzles, which are fed through the valve which this lever controls. The wheel, particularly its tire, is subjected to this steam as well as to the scrubbing action of the brushes. As the wheel continues to advance, gradually the second of levers 78 is moved rearwardly and steam is ejected from the second pair of nozzles 22 which are fed through the valve which this lever controls. As the flow of steam from the second pair of nozzles increases, the flow of steam from the first pair of nozzles gradually decreases because of the reduced pressure of the steam available to the first valve, which is still open. As the wheel continues to advance, it disengages the first lever and the flow of steam through the first valve is terminated. This process is continued until the entire wheel is cleaned. Nozzles 22 and brushes 20 act primarily on the periphery of the wheel, i. e., the tire. Nozzles 94 and 96 act primarily on the center of the wheel, i. e., the hub. Nozzle 100 rinses the wheel with hot water before it disengages frame 24. As one of the right wheels of the automobile is cleaned by the illustrated apparatus, the aligned left wheel of the automobile is cleaned by a similar apparatus. The length of frame 24 is such that the apparatus disengages the forward wheel of an automobile before it engages the rearward wheel, and disengages the rearward wheel, before it engages the forward wheel of the next automobile even if it follows bumper-to-bumper.

Since certain changes may be made in the above apparatus without departing from the scope of the invention herein involved, it is intended that all matter contained in the above description and shown in the accompanying drawings shall be interpreted in an illustrative and not in a limiting sense.

I claim as my invention:

1. Cleaning apparatus comprising an elongated base mounted for movement parallel to itself in a direction having a component perpendicular to its direction of elongation along a floor, a plurality of interspersed rotatable brushes and fluid nozzles distributed along said base with portions of said brushes and with mouths of said nozzles being disposed along a longitudinal edge of said base, said brushes being sufficient in number and sufficiently close to each other to scrub successive sections throughout the periphery of a tire rolling in contact therewith along said floor, said base being biased toward said tire.

2. Cleaning apparatus comprising an elongated base mounted for movement parallel to itself in a direction generally perpendicular to its direction of elongation, a plurality of interspersed rotatable brushes and steam nozzles distributed along said base with portions of said brushes and with mouths of said nozzles being disposed along an elongated edge of said base, said brushes being actuated by a common drive, a plurality of valves for respectively feeding a plurality of said steam nozzles, a plurality of arms mounted for movement on said base for respectively controlling said valves, said arms being movable independently of one another, said brushes being sufficiently close to each other to scrub overlapping sections of a wheel rolling in contact therewith, said base being biased toward said wheel, and means for contacting said wheel in order to limit movement of said base toward said wheel.

3. The apparatus of claim 2 wherein said base is cantilevered at the free ends of a pair of parallel swivel arms.

levered at the free ends of a pair of parallel swivel arms.

4. Cleaning apparatus comprising an elongated base mounted for movement parallel to itself in a direction having a component perpendicular to its direction of elongation, a plurality of interspersed rotatable brushes and steam nozzles distributed along said base with portions of said brushes and with mouths of said nozzles being disposed along an edge of said base, said brushes being sufficiently close to each other to scrub overlapping sections of a wheel rolling in contact therewith, said base being biased toward said wheel, and a plurality of arms pivoted to said base for controlling the discharge of steam from said nozzles, said arms being pivoted on said base adjacent to the nozzles they control, said arms projecting from said base obliquely away from that end of said base first to be contacted by said wheel.

5. The apparatus of claim 4 wherein the edges of said arms farthest from said base are provided with rotatable rollers that are elongated in the direction of elongation of said arms.

6. The apparatus of claim 4 wherein said base is cantilevered at the free ends of a pair of parallel swivel arms.

7. The apparatus of claim 4 wherein pivotal movement of said levers toward said base is limited by adjustable stops.

8. The apparatus of claim 4 wherein a main line having a steam inlet at the end of said base terminally contacting said wheel feeds said nozzles.

9. Cleaning apparatus comprising an elongated base mounted for movement parallel to itself in a direction substantially perpendicular to its direction of elongation, a plurality of interspersed rotatable brushes and steam nozzles distributed along said base with portions of the peripheries of said brushes and with mouths of said nozzles being disposed along an edge of said base, said brushes being sufficiently close to each other to scrub overlapping sections of a wheel rolling in contact therewith, said base being biased toward said wheel, and a plurality of arms pivoted to said base for controlling the discharge of steam from said nozzles, said arms being pivoted on said base adjacent to the nozzles they control, said arms projecting from said base obliquely away from that end of said base initially contacted by said wheel, the edges of said arms farthest from said base being provided with rotatable rollers that are elongated in the direction of elongation of said arms, and a main line feeding said nozzles, said main line having a steam inlet at the end of said base that terminally contact said wheel.

10. The apparatus of claim 9 wherein said base is cantilevered at the free ends of a pair of parallel swivel arms.

11. The apparatus of claim 9 wherein pivotal movement of said levers toward said base is limited by adjustable stops.

12. Cleaning apparatus comprising an elongated base contiguous with a floor, said base being movable parallel to itself in directions having components perpendicular to the direction of elongation of said base, a plurality of interspersed rotatable brushes and fluid nozzles distributed along said base and projecting therefrom generally in one of said directions, said brushes being actuated by a common drive, a plurality of valves for respectively feeding a plurality of said fluid nozzles, a plurality of arms mounted for movement on said base for respectively controlling said valves, said arms being movable independently of one another and projecting from said base, in said one of said directions, and means for biasing said base in said one of said directions, said brushes and said arms serving to contact a wheel rolling continuously on said floor along said base, said brushes being sufficient in number to scrub peripheral portions of said wheel.

13. Cleaning apparatus comprising an elongated base contiguous with a generally flat and smooth floor area, a pair of parallel swivel arms, rearward ends of said swivel arms being pivoted about axes perpendicular to said floor

area, forward ends of said swivel arms being pivoted to ends of said base, a plurality of interspersed rotatable brushes and fluid nozzles distributed along said base and projecting therefrom generally forwardly, said brushes being actuated by a common drive, a plurality of valves for respectively feeding a plurality of said fluid nozzles, a plurality of control arms mounted for movement on said base for respectively controlling said valves, said control arms being movable independently of one another and projecting generally forwardly from said base over a section of said floor area, and means for biasing said base generally forwardly, said brushes and said control arms

serving to contact a wheel rolling continuously on said section of said floor area.
